AIR CONDITIONING SYSTEM FOR
BUILDINGS

Hal Hayes, Los Angeles, Calif.

Application December 26, 1934, Serial No. 759,225

4 Claims. (Cl. 62—139)

This invention relates to means for heating, cooling, and humidifying air, and particularly pertains to an air conditioning system for buildings and the like.

5 At the present time the general public is becoming aware of a need for means to condition the air in buildings, particularly in dwellings, so that the air will have a uniform humidity and so that the temperature of the air may be controlled appropriately in hot and cold weather. 10 Most of the devices contemplating these results are installed as separate auxiliary units in rooms or dwellings. It is the principal object of the present invention to provide means for obtaining 15 the results previously described which is installed as an inherent part of a dwelling when built, and not only utilizes the usual heating structures for raising the temperature of the air but provides means whereby the walls, floors, and ceilings of rooms may be changed in temperature corresponding to the desired temperature required of 20 the air which is within the room.

The present invention contemplates the provision of a building structure of fireproof construction, said structure embodying means within the walls thereof to permit a cooling or heating medium to flow therethrough, and being provided with additional means for controlling the temperature of the air which is delivered directly to the room.

30 The invention is illustrated by way of example in the accompanying drawings in which:

Figure 1 is a view in vertical section through a portion of a dwelling indicating schematically an arrangement of the present invention.

35 Fig. 2 is an enlarged view in transverse section, as seen on the line 2—2 of Fig. 1, showing the wall construction of a building embodying the present invention.

40 Fig. 3 is a view in vertical section and elevation showing an air circulating method with which the present invention is concerned.

45 Fig. 4 is a fragmentary view in horizontal section through the floor of the dwelling as seen on the line 4—4 of Fig. 1, showing a method of heating the floor.

50 Referring particularly to Fig. 1 of the drawings a wall structure is shown made of reinforced concrete and constructed by the general method and means shown in my co-pending application entitled Concrete form, Serial No. 734,305, and filed by me July 9, 1934. In this type of construction the floor, walls, and ceilings of rooms are cast of concrete so that the building structure is substantially monolithic. Due

to this construction it will be evident that there will not be any fire hazard in embodying the features of the present invention in the structure. It is contemplated in forming a wall as here shown that the wall will have opposite plane sides 10 and 11 as particularly shown in Fig. 2 of the drawings, and that these sides will be connected at equal spaced intervals throughout their horizontal length by transverse webs 12 cast integral with the wall sections and thus 10 forming a plurality of parallel vertical passageways 13. These passageways, as shown in Fig. 1 of the drawings, extend substantially the height of the wall and communicate at alternate ends through transverse openings 14. It will therefore be recognized that the passageways 13 form a sinuous path of travel for air throughout the length of the wall. This sinuous passageway is utilized in the present instance to accommodate heated air or cooled air, the temperature of 20 which will be imparted to the entire wall structure and will thus be radiated from the wall surfaces within the room. In this manner a certain degree of temperature will be imparted to the air contained within the room, irrespective of circulation. For heating purposes the present invention contemplates the use of a hot air furnace, such as generally indicated at 15 in the drawings. This furnace has the usual firebox 16 and a circumscribing outer shell 17 30 which provides a fresh air circulating space 18. The products of combustion from the furnace are here shown as led off through pipes 19 and 20. The pipe 19 leads to a sinuous passageway 21 here shown as embedded within the floor 22 35 of the room. The passageway 21 may be cast in any suitable manner and may be lined with a permanent metal wall, such as obtained by the use of galvanized iron or other metal piping. The floor structure is formed of concrete and 40 is therefore fireproof. The exhaust end of the passageway 21 communicates with a flue 23 which extends upwardly through the wall and leads to a chimney 24. It may also be desirable to circulate the products of combustion through a section of the wall. This is done 45 through the pipe 20 to permit the smoke and burned gases to pass upwardly and along the wall passageways 13a and then out through a chimney 26. It will be evident that a large amount of 50 the heat which at the present time is lost incident to the operation of a furnace may be conserved due to the heat absorbed by the floor structure and the wall structure as the heated gases pass to the chimneys. When it is desired 55

to supply cool air to the room at a time when the furnace is not in operation fresh air is drawn inwardly from an outside register 27 to a passageway 28 and thence downwardly to the mouth of a blower 29. The fresh air is then drawn inwardly to the air space 18 within the shell 17, and may then be led through pipe 30 to passageways 13b in a section of the wall as indicated in Fig. 1. These passageways will conduct the cooled air along a sinuous path of travel and if desired may lead to and through a food storage cooler 31 before being introduced directly into the room through a wall register 32. In order to increase the cooling action upon the air passing through the passageways 13b it may be found desirable to provide the passageways with absorbent lining such as wick material indicated at 33 in the drawings. This material receives water delivered from a pipe 34 disposed above the ceiling of the room and which thereafter passes through a cooling coil 35 positioned within one of the vertical passageways of the wall. A return pipe 36 from this coil communicates with a distributing pipe 37 having feed pipes 38 leading therefrom. These pipes conduct water to the wick lining 33 of the passageways and thus insure that the evaporation of water from the wetted surface of the wall will lower the temperature of the air passing therethrough in a manner as may be well understood. In the first of the passageways 13b a spray head 25 is provided thus acting to dehumidify the air coming in from the furnace and passing through the passageways 13b. The cool air is delivered to the room through register 32 and may be drawn from the room in any suitable manner. A vane controlled air inlet 39 may be mounted in communication with the next succeeding air passageway 13b following the one within which dehumidification takes place to supply auxiliary air if desired. This may be appended at any point.

In the event it is desired to heat the room directly by introducing heated air from the furnace this may be done in the usual manner by conducting heated air from the furnace through a pipe 40 to a register 41. In some instances it may be desirable to obtain a cooling or heating effect upon the outside walls of the building by a free circulation of air. This is accomplished as shown in Fig. 3 of the drawings by forming a section of the wall with passageways 13c and providing wall registers 42 communicating with the outside of the room and through which air may flow to occupy the space within the wall.

In operation of the present invention, when a room is to be heated the flow of exhaust gases from the firebox 16 through pipe 20 to the wall passageways 13a is permitted. If desired, these gases may be directed through the heat pipes 21 and to the ducts 13a. The heat may then flow along the paths of travel defined by these passageways to the chimneys 24 and 26. It is also possible to introduce heated air from the furnace directly into the room or rooms through the pipe 40 and the registers 41.

In the event that it is desired to cool the dwelling fresh air is drawn in through the duct 28 by the suction fan 29 and after passing through the furnace 15, which at the time does not contain a fire, the air may be passed through any or all of the ducts and passageways leading to the wall. The cooled air passes through the pipe 30 to the first ducts 13b where the air is de-

humidified by spray 25, and then follows a sinuous path of travel along these ducts to the register 32. In the course of this travel the air will pass along wetted surfaces of the wick members 33 and the wall surfaces and along and around the water coil 35. This air will thus be reduced in temperature by evaporation. Attention is directed to the fact that the water cooling coil 35 is placed near the end of the path of travel of the air through the passageways 13b. Thus the air of lowest temperature will act on the coil to lower the temperature of the water used in the dehumidifying spray 25 and applied to the evaporation wicks 33. It will also be seen that the cooled water from the coil is led directly to the spray 25 so that the coolest water in the system will strike the warmest air flowing into the passageways 13b and thereby add to the efficiency of the apparatus.

When desired "make up" air may flow into the cooling system through member 39. It will thus be seen that due to the arrangement here disclosed it is possible to efficiently control the temperature and humidity of air in a room and to insure that this temperature will be uniformly maintained throughout the room.

While I have shown the preferred form of my invention, as now known to me, it will be understood that various changes may be made in the combination, construction, and arrangement of parts by those skilled in the art without departing from the spirit of the invention as claimed.

Having thus described my invention what I claim and desire to secure by Letters Patent is:

1. A building structure comprising a circumscribing wall having sinuous air passageways therewithin whereby a flow of air may be established within and along the wall to change the temperature of the same, wetted surfaces within said passageways, and over which said flowing air travels and by which the temperature of the air is lowered, and means for introducing the cooled air into the room at the end of its travel within the wall, a water circulating device within the wall and through which water flows to be thereafter delivered to the wetted surfaces.

2. A building structure comprising a circumscribing wall having sinuous air passageways therewithin whereby a flow of air may be established within and along the wall to change the temperature of the same, wetted surfaces within said passageways, and over which said flowing air travels and by which the temperature of the air is lowered, and means for introducing the cooled air into the room at the end of its travel within the wall, a water circulating device within the wall and through which water flows to be thereafter delivered to the wetted surfaces, and means for introducing said cooled water into the air stream within the wall at a point near the entry of the air stream to the wall whereby dehumidification of the air is brought about.

3. A building structure including a wall having a plurality of sinuous air passageways therein communicating with a source of air exterior of said wall and which air flows through said passageway, a water to air heat exchanger unit disposed in the path of flow of said air and through which cooling water may circulate, and a plurality of liquid contact units disposed in the sinuous passageways and to which water from said heat exchanger unit may be delivered to further cool the flowing air by evaporation.

4. A building construction including a wall by which the air contained within the building

is cooled, which wall is formed with parallel vertical wall sections between which vertical air passageways are formed connecting at alternate opposite ends whereby air may follow a sinuous path of travel through the wall from an outside source to the interior of the building structure of which the wall is a part, a water coil interposed within said wall and around which

said air flows and through which water may circulate and a plurality of wetted surfaces within the passageways, said surfaces being supplied with water which has passed through the coil and by which the air will be cooled by evaporation before being introduced into the room. 5
